UNITED STATES PATENT OFFICE.

CHARLES G. ROWLETTE, OF GRAND RAPIDS, MICHIGAN, ASSIGNOR, BY MESNE ASSIGNMENTS, TO FOREST V. DETWILER, OF POTTSTOWN, PENNSYLVANIA.

STOVE.

1,236,985.

Specification of Letters Patent. Patented Aug. 14, 1917.

Application filed August 17, 1914. Serial No. 857,061.

To all whom it may concern:

Be it known that I, CHARLES G. ROWLETTE, a citizen of the United States, residing at Grand Rapids, in the county of 5 Kent and State of Michigan, have invented new and useful Improvements in Stoves, of which the following is a specification.

My present invention relates to stoves, and its objects are to provide a cooking 10 stove in which the oven may be closed off from the other cooking operations, to form a hot-air containing and retaining chamber capable of serving as a so-called "fireless-cooker"; and further, to provide such means 15 for thus closing off the oven as will shut the passages to and from the oven and at the same time open a suitable outlet from the air-heating chamber and vice versa.

These, and other objects appearing here- 20 after, are attained by, and the invention finds preferable embodiment in, the structure hereinafter described and illustrated by the accompanying drawings, in which:—

Figure 1 is an elevation of a cooking 25 stove, partly in vertical section, embodying my invention:

Fig. 2 is a like fragmentary view of the same, showing the oven dampers in another position:

Fig. 3 is a vertical section of the same 30 parts, taken on line A—B of Fig. 2, the oven shelves being removed:

Fig. 4 is an enlarged detail view in perspective of one of the dampers; and

Fig. 5 is a fragmentary view, enlarged, of another damper and connected parts.

The stove, (designated generally 1), has an air-heating chamber indicated at 2 containing suitable heating apparatus, as gas 40 burners of common cooking-stove construction, not shown. Various cooking operations, as frying, broiling, etc., may be effected in or over this chamber, as by removing the stove lid indicated at 3. An outlet 4 permits the passage of the heated air to the outside of the stove, as to the pipe 5. A hot-air flue or passage 6 leads from the air-heating chamber to the oven 7, which 45 may be provided with suitable removable shelves 8. Through the vent 9 the air in

the oven may pass to the outside of the stove as to the pipe 10.

I provide means for closing and opening the said outlet, flue and vent, so arranged as to close the flue and vent and at the same 55 time open the outlet; and in another adjustment, to open the flue and vent and at the same time close the outlet. Preferably, these means comprise the damper 11 adapted to close the flue and the damper 12 adapted to close the outlet: these may be formed practically of one piece as shown in Fig. 4, and are slidably operated in vertical guides 13 by long links 14 whose upper ends are pivoted to the crank arms 15 on the rock 60 shaft 16 having the operating handle 17:

The vent is closed by a damper or valve 18 operated by links 19 pivotally connected to the crank arm 20 on said rock-shaft.

The crank arms 15 and 20 are so arranged 70 relatively to each other that when the handle is turned to open the outlet 4, (as shown in Fig. 1) the flue 6 and vent 9 are closed, and when the handle is turned to close the outlet 4 (as shown in Fig. 2) the flue 6 and 75 vent 9 are opened.

It will be seen that by this arrangement there is necessarily an open passage to the outside of the stove from the air-heating chamber and its gas burners at all times, 80 whereby accumulation of leaking gas with accompanying dangers is obviated: also, that hot-air may be admitted to the oven, and then the passages to and from it may be closed, in which condition it serves as a 85 "fireless cooker"; and at the same time other cooking operations, as frying, broiling, etc., may be going on.

Not confining myself to details of construction shown or described, I claim:— 90

1. In a stove, an air-heating chamber having an outlet to the outside of the stove, an oven having a vent to the outside of the stove, a hot-air flue leading from said chamber to the oven, and means for closing the 95 outlet and opening the flue and the vent and for opening the outlet and closing the flue and the vent.

2. In a stove, an air-heating chamber having an outlet to the outside of the stove, an 100

oven having a vent to the outside of the stove, a hot-air flue leading from said chamber to the oven, a damper adapted to close said outlet, a damper adapted to close said vent, 5 a damper adapted to close said flue, and means for closing the vent and flue dampers and opening the outlet damper and vice versa.

In testimony whereof I have hereunto set my hand in presence of subscribing wit- 10 nesses.

CHARLES G. ROWLETTE.
